UNITED STATES PATENT OFFICE.

HERMAN F. VOSHARDT, OF CHICAGO, ILLINOIS, ASSIGNOR TO FRIELEY-VOSHARDT COMPANY, OF CHICAGO, ILLINOIS, A CORPORATION OF ILLINOIS.

DESIGN FOR A SHEET-METAL PIPE-ELBOW.

No. 39,722.

Specification for Design.

Patented Dec. 22, 1908.

Application filed September 19, 1908. Serial No. 453,882. Term of patent 14 years.

To all whom it may concern:

Be it known that I, HERMAN F. VOSHARDT, a citizen of the United States, residing at Chicago, in the county of Cook and State of Illinois, have invented a new, original, and ornamental Design for Sheet-Metal Pipe-Elbows, of which the following is a specification, reference being had to the accompanying drawing, forming part thereof.

The drawing is a side elevation of a pipe elbow showing my new design.

I claim:

The ornamental design for a sheet-metal pipe elbow, as shown.

HERMAN F. VOSHARDT.
